UNITED STATES PATENT OFFICE

CHARLES T. MARTON, OF ROCHESTER, NEW YORK

SIGN EXHIBITOR

Application filed July 13, 1928. Serial No. 292,405.

My present invention relates to card and sign exhibition, and it has for its object to provide a simple, cheap, and durable sign and sign holder adapted more particularly for designating and displaying streets and street names. The invention contemplates the provision of a sign holder of this general character which can be set up and assembled without the use of separable nuts, bolts, screws, nails, or other fastening devices, and without the use of tools of any kind.

To these and other ends the invention resides in certain improvements and combinations of parts, all as will be hereinafter more fully described, the novel features being pointed out in the claims at the end of the specification.

In the drawings:

Fig. 1 is an elevation of a sign post, sign and sign holder constructed in accordance with and illustrating one embodiment of my invention;

Fig. 2 is a similar view taken at an angle of 90° as compared with Fig. 1;

Fig. 3 is a top plan view;

Fig. 4 is an enlarged fragmentary view partly in section on the line 4—4 of Fig. 1, but showing one of the lower sign holders removed;

Fig. 5 is a back view of one of the sign holders;

Fig. 6 is an enlarged elevation of the inside of one of the fastening devices;

Fig. 7 is a side view thereof;

Fig. 8 is an enlarged section taken on the line 8—8 of Fig. 6;

Fig. 9 is an enlarged section taken on the line 9—9 of Fig. 6;

Fig. 10 is a further enlarged view of the interior of a modified form of fastener;

Fig. 11 is a fragmentary perspective view of one end of one of the sign holders;

Fig. 12 is an enlarged fragmentary sectional view taken substantially on the line 12—12 of Fig. 4;

Fig. 13 is an enlarged section partly broken away taken in a horizontal plane through a pair of sign holders substantially on the line 13—13 of Fig. 2 and showing the form of fastener illustrated in Fig. 10, and

Fig. 14 is a section taken substantially on the line 14—14 of Fig. 13.

Similar reference numerals throughout the several views indicate the same parts.

Street signs of the character contemplated by my invention and in the construction of which it may be used to advantage, I usually place at street intersections that bear the names of both of the intersecting streets, one disposed at a 90° angle to that of the other. I have shown and will describe such a sign, although my invention includes the use of single street designations.

Referring more particularly to the drawings 1 indicates a sign post surrounded by the cap piece 2 secured thereto by set screws 3. This cap piece is preferably integrally formed in a single casting with upper and lower supporting elements 4 and 5 which are preferably flattened on their opposite side and directionally reversed from each other at an angle of 90°. The whole is surmounted by a decorative extension of the casting 6. A description of one of these supporting elements 4, 5 will suffice for both.

Each is provided in the present instance with four openings or sockets 7 as best shown in Figs. 4 and 12. I place on opposite sides of each support, back to back, a pair of sign holding plates 8 that may be conveniently made of sheet metal stampings. Each plate carries on its rear side a pair of projecting rivets or pins 9 which engage in the openings or sockets 7 in a complementary manner as indicated, the ends of the pins terminating flush with the opposite side of the support. These are to support and position the two sign holders.

Each such sign holder 8 is provided along its longitudinal or horizontal edges with a flange 10 that is adapted to slidably and removably and replaceably receive a sign plate 11. Such sign plates are usually and conveniently formed of a flat sheet of metal having a glass enamel coating that gives the street name on a background of a contrasting color. The ends of these retaining flanges 10 as clearly shown in Fig. 11 are cut back and the extreme edge of the plate at each end is turned rearwardly and in-

wardly again as indicated at 12 to constitute a sort of a hook or interlocking channel. As shown in Fig. 13 these hooks or channels are turned oppositely on each pair of signholding plates 8 at each end of the pair.

It will be seen that in the make up of the device I have so far described no fastenings other than the rivets or pins 9 have been used, and it is obvious that no tools are required to assemble these.

I secure the holding plates 8 back to back in this interlocking relationship against the support by means of a sliding detachable and replaceable fastening element, one form 15 of which made from cheap metal stamping is best shown in Figs. 13 and 14. It consists of a body portion 13 in the form of a channel member to the extremities of which are spot welded or otherwise secured on the 20 outer side ornamental corner pieces 14 that give the effect shown in Figs. 1 and 2 and also have functional utility. Within the channel member 13 are spot welded or otherwise secured a pair of oppositely spaced angle members 15 that meet in the center in 25 oppositely curved hook sections or channels 16. In assembling as the fasteners 13 are slipped down over the end of the holding plate 8. These portions interlock with the 30 corresponding flanges or hooks 12 of the plates 8 as clearly shown in Fig. 13. The sides of the members 13 form continuations of the edge flanges 10 of the plates 8 in both 35 clearance and function in confining the ends of the signs 11. It is for the reception of these members 13 that the flanges 10 are cut back as before described, and as best shown in Fig. 11, and the corner pieces 14, being offset, engage the outer surfaces of the 40 flanges 10, and interlock the sign holders at this point of contact also as well as concealing the joint and making the entire structure appear to be all in one piece.

As the fasteners 13 are slid in the plates 45 their ultimate position is defined by an inwardly turned top flange 17 that abuts against the top edges of the ends of the plates 8.

In Figs. 6 to 9 the modified form of fastener is shown which is integral and may be 50 die-cast instead of being built up from sheet metal stamping. The body thereof may have a central opening 18 with T-shaped 55 projections 19 at top and bottom to engage the oppositely turned flanges 12 of the plates 8 as before, and to interlock therewith at these points.

I claim:

1. In a street sign exhibitor, the combination 60 with a support and a pair of sign holders arranged back to back on opposite sides of the support and having therewith cooperating projecting and recessed positioning and supporting elements, said sign holders being provided with sign retaining flanges on

the longitudinal sides thereof, of fastening devices slidably engaged on the ends of the sign holders securing the latter together and against the support, said fastening devices being provided with flanges in continuation 70 of those on the sign holders for engaging and confining the ends of sign plates held therein.

2. In a street sign exhibitor, the combination 75 with a support and a pair of sign holders arranged back to back on opposite sides of the support and having therewith cooperating projecting and recessed positioning and supporting elements, said sign holders being provided with sign retaining flanges 80 on the longitudinal sides thereof and with inturned flanges at the ends thereof, of fastening devices slidably engaged on the ends of the sign holders and provided with oppositely turned interior flanges interlocking 85 with the inturned flanges of the sign holders, said fastening devices being provided with flanges in continuation of those on the sign holders for engaging and confining the ends 90 of the sign plates held therein.

3. In a street sign exhibitor, the combination 95 with a support and a pair of sign holders arranged back to back on opposite sides thereof, said sign holders being provided at their ends with inturned flanges, of fastening devices slidably engaging the ends of the sign holders to retain them against the support, said fastening devices being provided with oppositely turned interior flanges 100 interlocking with the inturned flanges of the sign holders.

CHARLES T. MARTON.
